CLAIM

The ornamental design for an air quality meter, as shown and described.

DESCRIPTION

FIG. 1 is a perspective view of an air quality meter showing my new design;

FIG. 2 is a top plan view thereof;

FIG. 3 is a rear elevational view thereof;

FIG. 4 is a left side view thereof;

FIG. 5 is a front elevational view thereof;

FIG. 6 is a right side view thereof; and,

FIG. 7 is a bottom plan view thereof.

The broken lines illustrate portions of the air quality meter that form no part of the claimed design.
